UNITED STATES PATENT OFFICE.

CHARLES T. McPHALEN, OF LOS ANGELES, CALIFORNIA.

TRUCK.

Application filed July 23, 1923. Serial No. 653,278.

To all whom it may concern:

Be it known that I, CHARLES T. McPHALEN, a citizen of Canada, and a resident of Los Angeles, county of Los Angeles, and 5 State of California, have invented a new and useful Truck, of which the following is a specification.

The present invention relates to improvements in trucks and its particular object is 10 to provide a truck that will allow of the convenient handling of a large slab of concrete for constructional purposes. It is particularly proposed to provide a truck of this character that may be pushed under a horizontally disposed slab, that may be raised to lift the slab off its original support and advanced to the building to be erected and that may thereafter be operated to turn the slab into a vertical position at a distance from 15 the axle of the truck. It is further proposed to provide means rendering the truck portable after a slab has been raised into a vertical position. It is further proposed to provide means in combination with this truck 20 whereby the slab, after being moved into the vertical position can be raised and lowered to suit the requirements of the case. Further objects and advantages of my device 25 will appear as the specification proceeds.

30 The preferred form of my invention is illustrated in the accompanying drawing in which Figure 1 shows a side view of my truck, Figure 2 a top plan view of the same, Figure 3 a side elevation with the bed of the 35 truck lifted to a vertical position, Figure 4 a perspective view of the front end of a frame member and Figure 5 a perspective view of a handle for operating a ratchet. While I have shown only the preferred form of my 40 invention I wish it to be understood that various changes and modifications may be made within the scope of the claims hereto attached without departing from the spirit of the invention.

45 The axle (1) is supported in two wheels (2) and has a drum (3) disposed on its central portion. A long frame (4) corresponding preferably to the size of the slab to be transported consists of the longitudinal 50 frame members (6) and a plurality of transverse frame members (7). A short frame (8) of similar construction is pivotally secured to the axle by means of bearings (9) so as to freely swing on the same, with the 55 rear end of the short frame exceeding in

length the front end of the same considerably as shown in the drawing. The long frame which is of the same width as the short frame is adapted to lie on the same and has brackets (11) depending from an intermediate portion of its front end adapted to pivotally engage the front end of the short frame by means of the pin (12).

In the rear end of the short frame is mounted, on a shaft (13), a sheave (14) 65 adapted to be rotated by means of a worm gear (16) disposed on the outside of the frame. This worm gear is engaged by a worm (17) supported in bearings (18) and adapted to be driven by means of a crank 70 handle (19) which engages the worm by means of a universal joint (21) which allows the position of the crank handle to be changed in case the width of the slab to be carried by the long frame exceeds the width 75 of the latter without interfering with the operation of the worm gear. Two cables (22) are secured to the front end of the long frame as shown at (23), passed around the drum (3) and secured with their other 80 ends to the sheave (14) so that when the latter is turned in the proper direction the rear end of the short frame will be swung downwardly while at the same time downward pull will be exerted on the front end 85 of the long frame. It should be noted that the weight of the two frames is distributed in such a manner that during the beginning of the operation the lowering of the rear end of the short frame will cause the long 90 frame to be lifted merely without changing its horizontal position due to the fact that the rear end of the long frame as counted from the pivot (12) is considerably longer than the front end and is adapted to thus 95 balance the pull exerted on the front end by the cable (22) until the rear end of the short frame reaches the ground surface as shown in dotted lines in Figure 1. As soon as this dotted line position is reached a further 100 turning of the sheave (14) will cause the long frame to tilt forwardly and to gradually assume the vertical position shown in Figure 3 while at the same time the two wheels are lifted off the ground. The front 105 end of the long frame is provided with two wheels (24) rotatable on short axles (26) and the rear end of the short frame is provided with similar wheels (27) on the axles (28). As soon as the front end of the long 110

frame and the rear end of the short frame reach the ground surface the whole device moves on the four small wheels (24) and (27). The front wheels (24) are adapted to

5 be actuated by means of ratchets (29) operated by the pawl (31') on a handle (32') which allows the position of the whole device to be adjusted very closely.

10 The front end of the long frame has clips (31) extending inwardly with arms (32) pivoted on the same which latter arms have wheels (33) mounted in their free ends. These wheels are disposed in the plane of the upper frame and may be projected to 15 extend beyond the wheel (24) by means of the toggle joint (34) comprising two lengths (36) engaging intermediate portions of the arms (32) and engaged at their free ends by the threaded member (37) which latter 20 may be actuated for longitudinal adjustment by a nut (39) held against longitudinal motion by washers (41) bearing on transverse frame members (7). It will be seen that when the wheels (33) are projected beyond 25 the wheels (24) they will take the load and will allow the front end of the device to be moved laterally.

30 A bracket (42) is mounted in the front end of each longitudinal frame member and provided with a short flange (43) for holding the slab when the upper frame is turned into a vertical position. The brackets are 35 slideable in groove (44) in the longitudinal frame members (6) and are confined in the grooves (44) by the slats (46). The extreme ends of the two brackets are engaged by cables or ropes (47) passing over sheaves (48) and (49) to be engaged by an eye-bolt (51) which latter may be pulled 40 upwardly by means of a nut (52) bearing on a washer (53) which latter is seated against one of the transverse frame members (7).

45 The operation of my device may be explained as follows. Assuming that cement slabs of suitable forms for the construction of a building have been made and are lying in horizontal position on suitable supports: The truck is pushed under each cement slab 50 and lifted by rotating the crank handle (19) into the dotted line position shown in Figure 1. The slab is thereby lifted off its support and the truck may be moved to within close proximity of the building 55 where the slab is to be applied. The operation is then continued by turning the crank (19) further until the slab reaches the vertical position shown in Figure 3. For close 60 adjustment the truck which is now resting on the four wheels (24) and (27) may be advanced or pulled backward by means of the handle (32'). If it is desired to move the slab sideways the nut (39) may be turned whereby the wheels (33) are forced 65 to take the load. To adjust the height of

the slab it is only necessary to turn the nut (52) so that the slab may be brought into the exact position required.

I claim:

1. In a truck of the character described 70 a single wheel supported axle, a short frame secured thereon, a longer frame adapted to lie on the short frame having an intermediate portion pivoted to the front end thereof so as to project beyond the same and an operative connection between the front end of the larger frame and the rear end of the short frame whereby the two ends may be drawn together while each describes an arc 75 around the pivot.

2. In a truck of the character described 80 a single wheel supported axle, a short frame secured thereon, a longer frame adapted to lie on the short frame having an intermediate portion pivoted to the front end thereof 85 so as to project beyond the same, a sheave mounted in the rear end of the short frame, a drum secured to the axle and a cable secured to the front end of the longer frame and the sheave passing under the drum, allowing the front end of the longer frame and the rear end of the short frame to be drawn together while describing arcs around the pivot when the sheave is rotated.

3. In a truck of the character described 90 a single wheel supported axle, a short frame secured thereon, a longer frame adapted to lie on the short frame having an intermediate portion pivoted to the front end thereof 95 so as to project beyond the same, a sheave mounted in the rear end of the short frame, a drum secured to the axle, a cable connecting the front end of the larger frame with the sheave and passing underneath the drum, a worm gear mounted coaxially with 100 the sheave and a worm engaging the same to impart rotary motion to the same for drawing the front end of the longer frame and the rear end of the short frame together 105 while describing arcs around the pivots.

4. In a truck of the character described, a single wheel supported axle, a short frame secured thereon, a longer frame adapted to lie on the short frame having an intermediate portion of its front end pivoted to the front end of the short frame and means for swinging the rear end of the short frame downwardly whereby the longer frame is raised having means embodied therein for simultaneously depressing the front end of 115 the longer frame to counterbalance the rear end for maintaining the longer frame in a substantially horizontal position.

5. In a truck of the character described, a single wheel supported axle, a frame supported thereby and means for swinging the frame into a vertical position at a distance from the axle, comprising a short frame interposed between the first frame and the axle 120 pivotally engaging the first frame at a dis- 130

tance from the axle and means for depressing the rear end of the short frame exerting a downward pull on the front end of the first frame.

5. 6. In a truck of the character described, a single wheel supported axle, a frame supported thereby and means for swinging the frame into a vertical position at a distance from the axle, comprising a short frame in-
10 terposed between the first frame and the axle pivotally engaging the first frame at a distance from the axle and means for depressing the rear end of the short frame exerting a downward pull on the front end
15 of the first frame, the front end of the first frame and the rear end of the short frame having wheels thereon for rendering the de- vice portable after the first frame has reached a vertical position.

7. In a truck of the character described, a 20 single wheel-supported axle, a frame sup- ported thereby, a short frame interposed be- tween the first frame and the axle engag- ing the first frame at a distance from the axle, means for depressing the rear end of the 25 short frame exerting a downward pull on the front end of the first frame whereby the latter is forced into a vertical position, lon- gitudinally disposed wheels mounted on the front end of the first frame and the rear 30 end of the short frame for rendering the de- vice portable after the first frame has reached a vertical position and transversely mounted wheels on the first frame having 35 means associated therewith for allowing them to take the weight of the first frame.

CHARLES T. McPHALEN.
